UNITED STATES PATENT OFFICE.

JOHN A. PERKINS, OF MINNEAPOLIS, MINNESOTA.

GRAIN SEPARATOR.

Application filed August 13, 1928. Serial No. 299,343.

This invention relates to new and useful improvements in grain separators and more particularly to the type employing a moving separator surface comprising a plurality of 5 pockets or indentations adapted to receive certain sized material and deliver it to a suitable receiving means. Material too large to enter the pockets is collected from the separator and delivered to a discharge opening. 10 The primary object of my present invention is to increase the separating capacity and efficiency of a machine of this type by providing a series of deflector blades positioned to receive the coarse refuse material that is 15 swept from the surface of the separator and advance it from one deflector to another toward the discharge opening. These deflectors may be used without any feeding spiral or auger, or such an auger may be provided at 20 the delivery or discharge opening only or at both openings with the intermediate section omitted, or the deflectors may be used with the spiral extending the full length of the operating shaft, preferably arranged on an incline. 25 If the shaft is arranged in a substantially horizontal position, to operate in the lower portion of the body of the material on the separator, then better results may be obtained by eliminating the intermediate section 30 of the spiral.

A further object is to provide means for changing the position of the deflector blades with respect to the flight of the material projected against them, thereby regulating the 35 feed of the material toward the discharge opening.

A further object is to arrange the deflectors in groups so that the material collected from each separator may be fed to the discharge 40 point independently of the corresponding material collected from the other separator; that is, where parallel cylindrical separators are provided.

A further object is to provide means for 45 mounting the groups of deflectors so that if desired, one group can be adjusted independently of the other group.

Other objects of the invention will appear 50 from the following detailed description.

In the accompanying drawings forming 55 part of this specification

Figure 1 is a cross-sectional view of my improved separator showing the general arrangement of the parts;

Figure 2 is a plan view of Figure 1 partially broken away to show the position of the

deflectors and the action of the grain when projected thereagainst by the action of the rotary brushes;

Figure 3 is a longitudinal sectional view on 60 the line 3—3 of Figure 1 showing the means for delivering the material to the separator and the discharge for the coarse material.

Figure 4 is an enlarged detail sectional view on the line 4—4 of Figure 2;

Figure 5 is a detailed sectional view showing a modified means for preventing the coarser material from being carried over by the rotary brushes;

Figure 6 is a view showing another form of 70 separator with the invention applied thereto; and

Figure 7 is a sectional plan view on the line 7—7 of Figure 6 showing the structure on a smaller scale.

In carrying out my invention I provide a grain separator having a traveling indented separating surface with cooperating means to prevent the coarser material such as oats, barley and other refuse from being carried along 80 by the separating surface, with a suitable delivering and discharging means and a series of deflectors against which the coarser material is thrown by said cooperating means and passed from one deflector to another to 85 the discharge.

A further provision includes two cylinders having peripheral surfaces provided with a plurality of indentations or pockets adapted to receive material of a certain size such as 90 wheat, which, falling into the indentations, is discharged into a suitable receptacle beneath the cylinders. A rotary brush is preferably mounted above each cylinder with its bristles substantially contacting therewith so 95 that the coarser material such as oats and refuse which may be carried by the indentations or pockets, will be brushed back into the mass of grain between the cylinders, a series of deflectors being mounted between the 100 two brushes against which the coarser material is delivered and deflected from one to the other toward the discharge opening, the deflectors being capable of adjustment to vary their angle to the direction of delivery of the 105 coarse material and thereby increase or decrease the feed of the material to the discharge.

In the selected embodiment of the invention here shown, for purposes of disclosure, 110 there is illustrated in Figure 1 a grain separator comprising a casing 2 having spaced cylind-

ders 3 rotatably mounted therein, each having its periphery provided with a plurality of indentations or pockets 4 adapted to receive and carry certain sized material upwardly for discharge into the spaces or gaps 5 provided between the outer portions of the cylinders and the walls of the casing 2. The material discharged into these gaps, such for example, as wheat, is delivered onto the inclined bottom walls 6 and from thence into a conveyor 7 arranged centrally of the machine and having a discharge at one end thereof.

The cylinders 3-3 are spaced apart as shown in Figure 1 and a spacing member 8 is interposed therebetween which preferably has concave surfaces 9 provided with a suitable packing such as felt or sheep-skin to prevent the material from dropping downwardly between the member 8 and the periphery of the two cylinders. The spacing member 8 has an A-shaped upper edge 11 which functions to direct all of the grain downwardly into contact with the peripheries of the two cylinders when the delivery of the grain to the separator ceases, thereby causing all of the material delivered into the separator to contact with the periphery of the cylinders. The spacing member 8 is supported upon a member 12 arranged longitudinally of the machine and having its opposed ends suitably secured to the end walls 13 and 14 of the separator casing.

The means for delivering the material into the separator is shown in Figure 3 and comprises a hopper 15 mounted upon a tubular casing 16 secured to the end wall 13. A feed auger or screw 17 is mounted within the tubular casing 16 upon a shaft 18 preferably extending the full length of the separator and having its ends supported in suitable bearings 19 and 21 as shown. The bearing 21 is mounted in a small housing 22 adjustably secured to the end wall 14 by means of bolts 23. This housing has a discharge 24 for the coarser material such as oats and barley, which communicates with a discharge opening 24^a, provided in the wall 14, as shown. The flange 25 of the housing 22 is provided with slots 26 adapted to receive the bolts 23 whereby the discharge 24 of the separator may be vertically adjusted. The bearings 19 and 20 are so constructed as to permit vertical adjustment of the housing 22 as will readily be seen by reference to Figure 3.

The portion of the wall 14 beneath the discharge opening 14^a, has the function of preventing the fine material from entering the discharge, and the wall portion 22^a of the housing 22 forms a continuation of the wall 14, as shown in Figure 3. Vertical adjustment of the housing 22 by means of the slots 26 and bolts 23, will have the effect of raising the discharge opening and increasing the height of the wall that prevents the discharge of the fine material.

The feed screw or auger, as shown plainly in Figure 2, has a spiral at its delivery end for the purpose of rapidly forcing the material into the machine and a corresponding spiral at the discharge for hastening the output of the coarse material at this point. The intermediate portion of the spiral is preferably omitted, for when the feed screw is arranged horizontally there is danger of the intermediate spiral feeding the wheat or other fine material toward the discharge as well as the coarser material. At the same time it is desirable to provide some means for collecting and hastening the discharge of the coarse material and with this end in view I provide first, means to dislodge and collect the coarse refuse material from the surface of the traveling separator and means to receive such collected refuse material and feed it rapidly and efficiently toward the discharge of the machine. I will now proceed to describe this feature of the machine in detail.

A rotary brush 27 is preferably arranged over each cylinder and each has its periphery substantially engaging the periphery of its respective cylinder so that all coarse material carried upwardly between the indentations in the cylinder periphery will be brushed back in a direction toward the center of the machine as indicated by the arrows in Figures 1 and 2. An angle plate 28 is arranged adjacent to each brush 27 and has one flange substantially engaging the periphery of its respective brush to prevent the coarse material from being carried around by the brushes. Each brush 27 is mounted on a shaft 29 mounted in suitable bearings provided in the end walls of the separator casing.

The function of each brush, as shown in Figures 1 and 2 and indicated by the arrows in these figures, is to dislodge or collect the oats and refuse material and sweep it inwardly toward the feed screw, thereby separating it from the mass of finer material that has been collected in the pockets of the separator. Cooperating with these brushes or other suitable collecting means of a similar function, I provide a plurality of deflectors or inclined plates 31, each having a pivot pin 32 secured thereto and journaled in suitable brackets 33 secured to the upper wall of the casing. An arm 34 is non-rotatably secured to each pivot pin 32 for relatively adjusting the position of its respective deflector plate 31. Each deflector plate is provided with such an adjusting arm as clearly shown in Figure 2. To provide means for simultaneously adjusting all of the deflectors each arm 34 has its swinging end pivotally engaged with an adjusting bar 35 slidably mounted upon the upper wall of the casing and having a hand grip 36 by means of which it may readily be adjusted to change the angular positions of the deflectors 31. A screw 37 is secured in the upper casing wall and traverses a slot 38 in

the bar 36. A wing nut 39 is terminally mounted upon the screw 37 for locking the adjusting bar 35 in adjusted positions.

An apron or guard 31^a depends between the groups of deflector plates and its function is to prevent the material from being thrown past one group of deflectors into the other group on the other side of the machine. Therefore in the operation of the machine the coarse refuse material that is collected by each brush will be delivered to its adjacent group of deflectors and be passed along from one deflector to the other in the same group until it reaches the discharge.

The deflectors are primarily intended to supplement the operation of the spiral or auger feeding means or other suitable device for this purpose and thereby increase the capacity of the machine. The spiral may have its middle portion omitted and provided with a short delivery auger at one end and a corresponding discharge auger at the other end, or the machine may be successfully operated by employing a group or series of deflectors and a means for directing the coarse material thereon without the use of a feed auger or other corresponding feed device. If a spiral is used and extends the full length of the feed shaft it should be set at an incline in the material and in this position will operate very efficiently in connection with the deflectors to separate the coarse from the fine material. In the drawings, however, I have preferably shown the middle portion of the spiral omitted, as better results may be obtained by this arrangement, particularly if the feed shaft extends through the lower portion of the mass of material on the separator, but do not confine myself to this arrangement as the spiral may be extended the full length of the shaft, if preferred, or the spiral or other feeding means may be entirely omitted and the deflectors used alone in cooperation with a suitable means for collecting the coarse material upon the separator.

A suitable chain drive 41 is provided at one end of the separator for operating the cylinders, brushes and conveyors. These parts are so connected as to rotate in the direction indicated by the arrows in Figure 1.

Figure 5 illustrates a modified construction wherein the angle plates 28 have been dispensed with and in place thereof a semi-cylindrical housing 42 is engaged with each brush 27 to prevent the coarser material from being carried over the tops of the brushes. These cylindrical housings may be supported upon the upper wall of the separator casing.

Figures 6 and 7 illustrate another modified form wherein the moving separating surface consists of an indented belt 43 movably mounted upon cylinders 44 and 45 and having an inclined wall 46 arranged adjacent the lower portion of the belt which substantially engages the surface thereof to prevent ma-

terial from passing between the surface of the belt and the lower offset portion 47 of the plate 46. This plate 46 cooperates with the inclined upper run of the belt to provide a hopper adapted to receive the material from a suitable chute or hopper 48 arranged adjacent one end thereof as shown.

A feed auger or screw 17^b corresponding substantially to the one described with reference to the previous figures is mounted in the machine and has a feed spiral as indicated for accelerating the initial movement of the material onto the separating belt and another discharge spiral near the discharge opening for hastening the output of the light refuse material from the machine. These spirals are mounted on a shaft 18 corresponding to the one previously described and the middle portion of the spiral is preferably omitted. A brush 53 is mounted in the upper portion of the separator and substantially engages the surface of the upper run of the belt 43 and functions to brush the oats and coarse refuse material backwardly in the direction indicated by the arrows in Figures 6 and 7.

A plurality of deflector plates 54 are hinged to the side wall 55 of the separator casing and each deflector has its upper edge pivotally connected to an adjusting bar 56 arranged beneath the top wall of the separator and having one end projecting from the casing as shown at the left hand side of Figure 7. A projecting end portion 57 provides a hand grip whereby the deflectors 54 may be moved back and forth and their angle changed with respect to the direction of flight of the material that is thrown against them by the brush 53 and thereby feed of the coarse material to the discharge may be controlled.

In Figure 7 I have shown the cylinders 44 and 45, the augers 17^b and 51 and the brush 53 driven by means of a chain drive 58 illustrated at the right hand end of the figure. Any other suitable driving mechanism may of course be substituted for this belt if preferred.

By the employment of the deflectors the feeding of the coarse material lengthwise of the machine may be controlled at will. For example, should the feeding of the material into the separator be uneven or intermittent the positions of the deflectors 31 may be so adjusted as to retard or speed up the feeding of the coarser material through the machine depending upon the character of the material being separated so that a thorough separation may be obtained of all materials, one from the other. In the drawings I have shown the deflectors mounted for relative adjustment, and all connected with the adjusting bar 35 so that they will be moved simultaneously when the bar is longitudinally moved. It is to be understood, however, that if desired the deflectors may be arranged in groups and each group adapted

for adjustment independently of the other group so that the coarser material may be caused to travel faster through one portion of the machine than through the other portion. In some instances it may be desirable to mount the deflectors in fixed relation with respect to the cylinders or separating surfaces.

The A-shaped spacing member 8 mounted 10 between the cylinders 3-3 provides means for delivering all of the material received in the separator between the two cylinders onto the peripheries thereof so that when the feeding of the material to the separator 15 through the hopper 15 ceases all material delivered into the separator will be subjected to the action of the separating surfaces of the two cylinders and consequently all fine and coarse material delivered into the separator 20 will be separated one from the other.

In the operation of the machine the material to be separated, usually wheat mixed with oats, barley and coarse refuse material, is fed into the machine at the delivery opening 25 and the auger or spiral at this point insures a rapid positive feed onto the separating surface. The mass of material collecting between the cylinders is engaged by their peripheral surfaces and carried upwardly 30 through the rotation of the cylinders, the fine material such as the wheat kernels, entering the pockets of the cylinders and becoming thereby separated from the coarse material. The continued rotation of the cylinders will discharge the seeds in the pockets 35 by gravity into a suitable receptacle as described, and the oat kernels and other material too large to enter the pockets will be engaged by the bristles of the brushes and dislodged from the separator and thrown inwardly against the deflector blades that are arranged at an angle to the direction of flight 40 of the material. These blades being arranged in groups, one for each separator, 45 serve to deflect the material thrown against them and advance it through the machine toward the discharge opening, where, as the final step in the operation, the refuse is engaged by the discharge spiral and quickly 50 ejected from the machine. The angle of these deflector blades to the work can be easily and quickly changed to suit different conditions, and to obtain the best results, and the use of these blades in connection with the 55 brushes may eliminate entirely the intermediate spiral of the feed auger; that is, the part between the delivery and discharge augers, and at the same time avoid the possible collection of the fine material by such 60 portion of the auger and its delivery to the discharge opening. The mass of material is distributed over the surface of the rotating separators and the brushes operating thereon will rapidly and thoroughly project the 65 coarse material against the deflector blades,

thereby separating it effectually from the wheat kernels which are collected in the pockets of the moving separators. The same principle is involved in the modification where an endless separator belt is shown in 70 place of the cylindrical separators. In the modification, one group of the deflector blades is provided with means for shifting them back and forth to change their angle with respect to the material that is discharged 75 against them. The manner of advancing or passing this material collected by the brush toward the discharge opening is, however, substantially the same in the modified construction as in the one first described. 80

In various ways the details of construction herein shown and described may be modified and still be within the scope of my invention.

I claim:

1. A machine of the class described comprising a suitable casing, a traveling separator therein having indentations or pockets to receive the finer material delivered thereto, said casing having a suitable discharge, means for collecting the light refuse material carried along by said separator and directing it away from the separator and means for deflecting such material to said discharge opening. 85

2. In a machine of the class described, a moving separator having a surface for separating wheat and fine material from a coarser material, means for sweeping the light refuse material off the surface of the separator and means in the path of such refuse material for 90 engaging and deflecting it to a suitable discharge. 100

3. A machine of the class described having a discharge opening for the light refuse material, means having pockets or indentations therein to receive and collect the finer material, normally stationary means for directing the light coarse material toward said discharge and means for collecting such material as it accumulates on said indented 105 means and directing it against said stationary means. 110

4. A machine of the class described, having means for delivering the material to be separated thereto and a suitable discharge for the coarse refuse material, a separator having pockets or indentations to receive the finer material, means arranged at an angle to the traveling material for directing the coarse, refuse toward said discharge, and 115 means for sweeping the refuse material from said separator against said angled means. 120

5. A machine of the class described, having receiving and discharge openings, a traveling separator having pockets or indentations to receive the finer material, and means for collecting the refuse material that is too large to enter said pockets and projecting it away from said separator, a series 125 of deflectors arranged in the path of the ref. 130

use material and at an angle thereto and means for changing the angle of said deflectors to the moving material.

6. A machine of the class described having means for delivering the material to be separated thereto and a suitable discharge for the coarse refuse material, a separator having pockets or indentations to receive the finer material, a series of deflector blades arranged in parallel relation between said receiving and discharge openings and adapted to direct the light coarse material from one blade to another toward said discharge, and means for brushing the surface of the separator and dislodging therefrom the light refuse material that is too coarse to enter said pockets and projecting such refuse material against the surfaces of said blades.

7. A machine of the class described having means for delivering the material to be separated thereto and a suitable discharge for the coarse refuse material, a separator having pockets or indentations to receive the finer material, a series of deflector blades arranged in parallel relation between said receiving and discharge openings and adapted to direct the light coarse material from one blade to another toward said discharge, and means for brushing the surface of the separator and dislodging therefrom the light refuse material that is too coarse to enter said pockets and projecting such refuse material against the surfaces of said blades, and said blades being capable of adjustment to change their angle to the flight of the material thrown against them.

8. In a machine of the class described, a pair of cylinders arranged at an incline in parallel relation and having peripheral indentations or pockets to receive and collect the finer material delivered thereto, means adjacent each cylinder for sweeping the coarse refuse material from the surface thereof and directing it to a point between said cylinders, and means in the path of the coarse refuse material for directing such refuse to a suitable discharge.

9. The combination with a pair of cylindrical separators arranged at an incline in parallel relation and having a series of pockets or indentations therein, of a series of deflectors mounted adjacent to said cylinders and adapted to receive the coarse refuse material and deliver it to a suitable discharge, and brushes arranged to sweep the coarse refuse material from the surface of said separators and direct it against said deflectors.

10. The combination with a pair of cylindrical separators arranged at an incline in parallel relation and having a series of pockets or indentations therein, of a series of deflectors mounted adjacent to said cylinders and adapted to receive the coarse refuse material and deliver it to a discharge, means for adjusting said deflectors to change their po-

sition with respect to said separators, and means mounted adjacent said separators for removing the coarse refuse material therefrom and projecting it against said deflectors.

11. The combination with a traveling separator having indentations or pockets therein to receive the finer material, of a plurality of deflectors adapted to receive the coarse refuse material and direct it away from the main body of the material and means for shifting said deflectors to change their angle to the material to be deflected.

12. The combination with a pair of rotating cylinders arranged at an incline in parallel relation and having pockets or indentations in their surface, of a group of deflectors arranged in spaced relation above each cylinder, said deflectors being arranged at an angle to the moving coarse, refuse material, being separated and adapted to deflect such material away from the mass of other material, and means in connection with each cylinder for discharging the coarse, refuse material against said deflectors.

13. In a machine of the class described, having receiving and discharge openings, a traveling separator having indentations or pockets in its surface to receive the fine material, a delivery auger for hastening the initial feed of the material to said separator, a discharge auger for accelerating the discharge of the light coarse material, means for sweeping up the light coarse material that accumulates on the surface of the separator and discharging it therefrom, and means interposed between said receiving and discharge openings for engaging the light, refuse material collected from the separator and directing such material to said discharge.

14. In a machine of the class described, having receiving and discharge openings, a traveling separator having indentations or pockets in its surface to receive the fine material, a delivery auger for hastening the initial feed of the material to said separator, a discharge auger for accelerating the discharge of the light coarse material, means for sweeping up the light coarse material that accumulates on the surface of the separator and discharging it therefrom, deflector means interposed between said receiving and discharge openings for engaging the light, refuse material collected from the separator and directing such material to said discharge, and means for shifting said deflectors to change their angle with respect to the flight of the material delivered thereon.

15. In a machine of the class described, having receiving and discharge openings, a means for accelerating the initial feed and hastening the discharge of the light refuse material, a separating member whereon the material to be separated is delivered in a mass, said separating member having pockets or indentations adapted to receive the fine ma-

terial, the light coarse material being too large to enter said pockets, means for collecting the light coarse material as it accumulates on said separating member and projecting it therefrom, and a series of deflector blades positioned to receive the light coarse material so projected and pass it along from one deflector to another to said discharge.

16. In a machine of the class described, rotating separators having peripheral pockets or indentations adapted to receive the fine material delivered thereto, said pockets being too small to receive the coarse material, means for collecting the coarse material as it accumulates on said separators and projecting it therefrom, groups of deflector plates arranged to receive the material so projected and advance it toward a discharge opening, and a guard or shield depending between the groups of deflectors and preventing the material from being thrown from one group into the adjacent group.

17. In a machine of the class described, a moving separator having a surface for separating fine from coarse material and provided with a discharge for said coarse material, and a group of deflector blades against which the coarse material is thrown and directed by said blades to said discharge.

18. In a machine of the class described, moving separators having surfaces for sep-

arating fine from coarse material and provided with a discharge for said coarse material, and groups of deflectors arranged in parallel relation and adapted to receive respectively the coarse material from said separator and deflect it toward said discharge opening.

19. In a machine of the class described, moving separators having surfaces for separating fine from coarse material and provided with a discharge for said coarse material, groups of deflectors arranged in parallel relation and adapted to receive respectively the coarse material from said separators and deflect it toward said discharge opening, and means preventing the material from being thrown from one group into the adjacent group.

20. In a machine of the class described, a moving separator having a surface for separating fine from coarse material and provided with a discharge for said coarse material, a group of deflector blades against which the coarse material is thrown and directed by said blades to said discharge, and means for vertically adjusting said discharge opening to prevent discharge of the fine material therethrough.

In witness whereof, I have hereunto set my hand this 10th day of August, 1928.

JOHN A. PERKINS.
